DISPLAY DEVICE AND DRIVE THEREFOR

Charles Roberts, New York, N. Y., assignor to
 Multiposter Advertising Corporation, New
 York, N. Y., a corporation of New York

Application November 13, 1936, Serial No. 110,574

17 Claims. (Cl. 40—36)

This invention relates to a device for displaying a plurality of advertising or display sheets in locations wherein it has been impossible up to this time to locate mechanical bulletins for the reason 5 that the thickness of such devices prohibited their installation.

To illustrate such locations, for instance, in a Pullman car passageway, the entrance passageway in the front of a bus and other such positions 10 where the thickness of a display bulletin must be under two inches. However, with such a wafer type of machine, the capacity of the machine must be such as to hold at least thirty sheets of advertising matter, shown serially, one after the other, in the display window of the machine.

A further object of my invention in such a machine is to devise a display mechanism which will be shock-proof and in which the display sheets can be quickly changed during the relative 20 short and infrequent times available for such change. A further feature of the invention is the novel type of holder which sustains the advertising sheet within the machine. This holder not only facilitates the quick change of advertising matter held therein, but, due to its peculiar form, it co-operates with a very simple means of intermittently moving each holder along the operative 25 circuit of the machine to properly display in timed sequence the advertising matter which it sustains. The holder of the advertising matter, therefore, is an integral part of this invention which permits my display device to be built within the minimum thickness, as I have above outlined, 30 and still maintain its maximum capacity of display sheets.

A further object of my invention is to so spread out the torque over the cycle of the device necessary for its operation that it can be readily operated by a small flexible shaft of considerable 40 length, as for instance, if the device is installed in a taxicab and the flexible shaft extends as far forward as the fan belt of the taxicab motor.

My invention is further incorporated in a novel 45 structure and relation of co-operating parts which permit of its peculiar contour for installation in passageway and other space restricted display locations. It is to be understood that the embodiment shown herewith is a preferred embodiment 50 only in order to properly illustrate the principles involved in my invention.

Referring to the drawings, Fig. 1 shows my invention in front elevation with the casing removed and showing certain parts in full section.

55 Fig. 2 is a section taken on line 2—2, Fig. 1,

and shows clearly the extent of the magazine of holders filling the entire side in which the display window is located, as well as both ends of the elongated circuit around which they pass.

Fig. 3 is a section taken on line 3—3 in Fig. 1. 5

Fig. 4 is a section taken on line 4—4, also in Fig. 1.

Fig. 5 shows clearly in perspective the novel holder or frame used in my invention, together with the advertising sheet alongside and about 10 to be inserted into the needle-like aperture of my novel frame. The advertising sheet is shown folded over on one of its edges ready to be inserted in the holder.

Fig. 6 shows the advertising sheet and holder in 15 perspective as the sheet is being entered into the holder.

Fig. 7 shows the completion of this operation of loading the holder with its advertising sheet. In Figs. 5, 6 and 7, the side of the holders is shown 20 with its novel side openings which co-operate with mechanism in my display device to convey and lock the holders.

Fig. 8 is a section taken on line 8—8, in Fig. 7.

Fig. 9 is a section in elevation made to graphically illustrate the co-operation of the side openings in the holder as shown in perspective in Figs. 5, 6 and 7 with the carrier pins and locking bar. 25

Fig. 10 is a schematic section of my invention showing the first of a series of progressive positions to illustrate the carrier pin, locking bar and pusher pawl. This view also shows the blank portion of each display sheet marked Z in relation to the extent of the window which comprises the display portion of the sheet. 30

Fig. 11 is the next succeeding position to Fig. 10 showing the relative positions of the holder No. 1, locking bar and pusher pawl. 35

Fig. 12 is similar to Fig. 11 but at a succeeding position. 40

Fig. 13 shows in section the speed control as used to operate my invention at constant speed as and when installed in vehicles which move at varying speeds. 45

Fig. 14 is an assembly in elevation and in perspective showing clearly the wafer-like dimensions of my invention with the flexible drive shaft and speed control, as preferably used to operate it when installed in motor operated vehicles, and the motor of the vehicle is shown in phantom. 50 This installation has proved to be very practical.

Referring more particularly to the drawings, in Fig. 1, numeral 1 is the cabinet of my display device having a window 2 incorporated on the front side thereof, see Fig. 2. A top plate 3 and bottom 55

plate 4 are held in spaced relation by panel 5 secured to the top and bottom plates by screws 6. Numeral 7 indicates the track in both the top and bottom plates in which the display holders 8 slide, forming the elongated circuit of my device. Sprockets 9 and 10 are fixed in bearings 11 and 12 respectively, secured in panel 5. Sprockets 13 and 14 turn in bearings 15 and 16 and carry chains 17 and 18 which also pass over sprockets 10 11 and 12. A U shaped cross head 20 slidably guided by pins 21, 22, 23 and 24 supports bearings 15 and 16, and the springs 25 attached at one end to pins 26 secured in panel 5 and the other end attached to pins 27, cause the chains 17 and 15 18 to be always under tension and to automatically absorb stretch. The lugs 28 and 29, respectively secured on chains 18 and 17, perform the following essential functions, as the chains 17 and 18 move on their sprockets driven by shaft 31, see Fig. 1, which is journaled in bearings 32 and 33, by virtue of worms 34 and 35 secured to shaft 31. They engage worm wheels 36 and 37 respectively which are secured to the hub of the sprockets 9 and 10, see Fig. 4, and in this manner the 20 sprockets rotate in direction of arrows A and B, causing the lugs 28 and 29 to move across the distance between the two pairs of sprockets on which chains 17 and 18 mesh in unison, as seen in Fig. 1. The lugs 28 and 29 are about to enter 25 the cut-outs 38 and 39, see Fig. 5, in the side of display holder C. It is to be noted that the side cut-outs in the sides of the holders are slightly different on each side, see section of holder in Fig. 9. In this manner, as lugs 28 and 29 pass 30 around the circumference of sprockets 13 and 14 their direction is reversed and they both press against the solid portion of frame C at 40 and 41, see Fig. 9, and start to advance frame C across the length of the machine. Just before the lugs 35 40 contact with surfaces 40 and 41, the other end of lug or pin 28, see Fig. 3, which is numbered 39, contacts with the face of arm 42 which is fulcrumed at 43 and has a bell crank arm 44 resting against pin 45 under tension of spring 46, arm 45 42 is depressed by the progress of lug 39 as it passes around the arc of sprocket 16 and assumes the position as shown in Fig. 9, wherein pin 39 is just about to pass off of face 42—a having depressed arm 42. A boss 47 on arm 42, see Fig. 9, 50 is likewise depressed and is shown just clearing opening 48 in the side of display holder C so that as pins 28 and 29 start to advance forward as they complete the arc of sprockets 14 and 13, display holder C is mechanically unlocked. Now in 55 contrast to this unlocked position, note, in Fig. 1, that the boss 47 in its normal position on arm 42 is bearing up against the surface 40, see Fig. 9, showing the holder C in section, so that holder C cannot advance. 60 Continuing the next step in the cycle, see Fig. 9, as pins 28 and 29 carry display holder C forward across the gap Y, see Fig. 2, formed by the extremities of the compacted display holders extending completely around one side of the elongated operative circuit, including both circular ends, the pin 28 contacts with arm 50, see Fig. 9, and pushes it forward to position 50—a with lug 28 at 28—a, arm 50 being fulcrumed at 51 and held in a normal position by its bell crank arm 65 52 to which is attached the tension spring 53 in a straight line to pin 54, and off-set arm 55 linked to lever arm 50 at 56 moves forward as arm 50 is forced forward by lug 28, arm 55 is retained in an 70 approximately parallel movement by a cross head 75

formed by two roller pins 56 and 57. On the extremity of arm 55 is a pawl bar 59 retained in a position, as seen in Fig. 2, by spring 60 and stop 61. Therefore as pawl bar 59 moves forward, actuated by arm 55, it contacts with the rearmost display holder D, see Fig. 9, pushing it forward to dotted lever position D—a. Likewise, as the rear-most holder is forced forward, it contacts with the next holder and so on, moving all the display holders in the compacted magazine the 10 width of one frame, or that frame, now in transit across the empty space in the circuit. These sequential movements are very graphically shown in Figs. 10, 11 and 12, which schematically show in Fig. 10 display holder C locked by boss or bar 15 lock 47 and pin or lug 28 about to carry holder C forward. In Fig. 11, you see boss depressed having just allowed holder C to pass forward carried by lug 28 and pusher pawl 59 about to contact with holder D. In Fig. 12, boss lock 47 has returned to its locked position, holder C is further advanced, and pawl 59 has pushed holder D ahead the width of one frame, bringing frame E into display position. 20

It is to be specifically noted that the sprockets 25 9, 10, 13 and 14 are vertical to the plane in which the elongated tracks, which guide the display holders, lay in. If the sprockets were, for instance, horizontal, they would have to be extremely small in order to be inserted into such 30 a narrow elongated track circuit. A chain running over such small sprockets causes chain wear and also pulls hard which is detrimental to a flexible shaft drive. For this reason, I purposely place the sprockets vertical which permits the 35 use of a good size sprocket and also makes possible my simple system of display movement by using a pin on the chain which enters the frame through a cut-out on one side and contacts with the opposite side of the display holder to pull it along 40 in its circuit.

Referring to Figs. 5, 6, 7 and 8, numeral 62 shows the base of my display holder. This base is that part of my frame which travels in track 7, see Fig. 4, and may be made unitary with the 45 double folded portion into which the display sheet 66 enters at the top end thereof, the base 62 may be made a separate portion attached thereto in any well known manner. The folded portion of my holder which acts as a lock for the display 50 sheet is seen clearly in Fig. 8, when the metal 67 has been folded in on itself to form a U shaped orifice providing an easy entry therein for the sheet which has had one edge thereof folded over prior to its entry, see Fig. 5. The top position of 55 the folded metal is preferably cut away at its top, see numeral 63, in Fig. 5, likewise section 64, to make the entry of the paper more easy to accomplish. A stop 65 prevents the paper sheet 66 from passing too far through the U shaped orifice in 60 the holder.

The means of operating my wafer type display device in a motor vehicle is a very difficult engineering problem. An electric drive for this device by its continuous use is very apt to overload 65 the storage battery. On the other hand, a vacuum motor will not operate if the car goes up grade as and when the butterfly valve in the carburetor is wide open. I have, therefore, devised a form of drive which, under actual test, has 70 proved very satisfactory and practical. The modern motor is completely enclosed. There are no uncovered secondary shafts such as magneto or pump shaft exterior to the crank case and available to connect to drive my display device. 75

hence by using a speed governor and adapting it to obtain a direct drive at a relative high speed off of the fan belt of the motor, even when the motor is idling, I can obtain sufficient R. P. M. to operate the flexible shaft which I use to connect the governor with the display device. Furthermore, it is necessary to obtain a speed of at least 600 R. P. M. on the flexible shaft to prevent a flutter in the display device mechanism, even taking into account the design of my novel structure to obtain low torque operation. I consider my system of drive, therefore, very valuable.

Referring to Fig. 13, 81 is the casing in which flexible shaft 82 is encased and which extends directly to the display device, see Fig. 14, numeral 83 is the driving pulley shown in enlarged detail in Fig. 13, including a main casing 85, a shaft 84 which terminates in a disc 86 from which spacers 87 carry a metal friction plate 105. On each side of this plate 105 are felt discs 89 and 90. An end thrust metal disc 91 is secured to shaft 106 which floats in recess 107 in shaft 84. A second disc 92 is keyed to shaft 106 but is capable of lengthwise movement axially on shaft 106. A member 94 secured by pin 104 to shaft 106 supports the bell crank arms 96 and 98 terminating in weights 97. The pins 108, slidably in member 94, are secured to grooved collar 95 which is under tension of spring 109.

The operation of my governor is manifest. The spring 109 retains the weights 97 in a position, as shown in Fig. 13, thereby compressing the felt discs 89 and 90 and causing flexible shaft 82 to rotate in accordance with the speed of the fan belt pulley 83. As and when the revolutions increase to a predetermined degree, the weights fly outward overcoming the spring tension and the felt discs are relieved of their frictional contact. In this manner, I attain a very even revolution on shaft 82 irrespective of the speed fluctuations of the pulley 83, and hence, an attractive and even operation of my display device under all operating conditions.

I do not wish to restrict the scope of the use of my display device to motor vehicles, yet the effort to produce a wafer machine to fit in the restricted spaces necessary for this service, together with an easily installed and practical mode of driving such a device, has been the paramount theme of this invention.

What I wish to encompass by United States Letters Patent is set forth in the appended claims.

I claim:

1. In a display device having a window therefor and comprising an elongated track circuit horizontal to and traversing said window, display holders movably restrained in said track circuit, a motor driven conveyor circuit within said track circuit, and a magazine for said holders composed of that portion of said track circuit embracing both ends thereof and including the side traversing said window filled with compacted display holders.

2. In a display device having a window therefor and comprising an elongated track circuit horizontal to and traversing said window, display holders movably restrained in said track circuit, a motor driven conveyor circuit within said track circuit and a magazine for said holders embracing both ends of said track circuit including the side traversing said window, and conveyor means co-operating with said circuit to move one holder at a time through that portion of said circuit empty of said display holders.

3. In a display device having a window there-

for and comprising a plurality of display holders movably restrained in an elongated closed circuit, said circuit traversing said window along its major axis, said holders completely filling said circuit on that side traversing said window, together with the two ends of said elongated circuit, such that that portion of said circuit left unfilled with said holders is substantially equal in length and on the opposite side to said window in said circuit, and motor driven conveyor means to move said holders, one at a time seriatim, across said empty portion of said circuit.

4. A display device for motor vehicle installation including an internal combustion motor therefor and having a fan belt driven by said motor and comprising a window in said device, and means for displaying a plurality of displays seriatim past said window, motive actuating means for said device connecting said device to said fan belt of the motor in said vehicle, comprising a speed governor actuated by said fan belt and a flexible shaft connecting said governor with said device.

5. A display holder to hold a display sheet in a display device of the type described, comprising a base, a metal superstructure secured thereto and formed with a double fold of metal, said double fold spaced apart to permit a display sheet folded at one end thereof to enter lengthwise into said double fold, thereby constituting a lock against any pull on said display sheet at right angles to said double fold.

6. In a display device having a window therefor and comprising a compacted group of display holders movably restrained in a closed circuit, motive operated conveyor means to move one of said holders at a time along the empty portion of said circuit, said conveyor means sustained by two pulleys mounted normal to and within the plane of said closed circuit, a projection on said conveyor adapted to engage one of said holders as and when it passes over one of said pulleys and to disengage said holder when it passes over the other of said pulleys, and means to advance said compacted group of holders in said circuit during the interval of said engagement and disengagement.

7. In a display device having a window therefor and comprising a compacted group of display holders movably restrained in an elongated horizontal circuit therein, motor operated conveyor means located within and normal to said circuit, means on said conveyor and co-operating means on the back of said holders to permit said conveyor to engage said holders, one at a time, at one end of said elongated circuit and to disengage said holder at the other end of said circuit.

8. In a display device having a window therefor, an elongated horizontal circuit having circular ends therein and supporting a plurality of display holders movably restrained thereby, motor operated conveyor means carried on two rotating supports mounted parallel to and within said circuit, a projection on said conveyor means, the circumference of said rotating supports for said conveyor in respect to the circumference of said circular ends of said circuit being so proportioned that said projection, co-operating with said holders in said circuit, engages said holders, one at a time, at one end of said elongated circuit and disengages said holders at the other end of said circuit.

9. In a display device having a window therefor and comprising a compacted group of display holders movably restrained in an elongated closed

- circuit horizontal to said window, motive operated conveyor means to move said holders, one at a time, along the empty portion of said circuit, said conveyor means mounted on two pulleys, the axis 5 of which is normal in respect to said closed circuit, and means on said conveyor to engage said holders, one at a time, when passing over one of said pulleys and to disengage said holder when passing over the other of said pulleys.
10. In a display device having a window therefor and comprising a plurality of display holders movably restrained in a closed circuit, the major axis of which is parallel to said window, motive means to convey said holders past said window, said conveyor means supported on two pulleys, said pulleys mounted parallel to the plane of and within said closed circuit, and a projection on said conveyor means adapted to engage the back of said holders, one at a time, at one 15 end of said circuit and to disengage from said holders at the other end of said circuit as and when said projection passes over said pulleys.
11. In a display device having a window therefor and comprising an elongated track circuit 20 horizontal to and traversing said window, display holders movably restrained in said track, a motive driven conveyor circuit normal to and within said track circuit, a projection on said conveyor circuit, means due to the relative length 25 of the track circuit as compared with the conveyor circuit to engage said projection with one of said display holders as and when said projection reaches the extremity of said conveyor circuit and to disengage said holder when it reaches 30 the other extremity of said circuit.
12. In a display device having a window therefor and comprising an elongated track circuit horizontal to and traversing said window, display 35 holders movably restrained in said circuit, a motor driven conveyor circuit within said track circuit, and a magazine for said holders composed of that portion of said track circuit including the side traversing said window and extending beyond said window to include the extremities of said elongated track circuit.
13. A display device for motor vehicle installation including an internal combustion motor therefor and having a fan belt driven by said motor and comprising a window in said device, and means for displaying a plurality of displays 40 seriatim past said window, motive actuating 45 means for said device connecting said device to said fan belt of the motor in said vehicle, comprising a speed governor actuated by said fan belt, and connecting means operatively connecting said governor with said device. 5
14. In a display device having a window therefor and comprising an elongated track circuit horizontal to and traversing said window, display holders movably restrained in said circuit, a magazine for said holders composed of that portion of said track circuit including the side traversing said window and extending beyond said window to include the extremities of said elongated track circuit, and motor driven means to convey one holder at a time from one extremity 10 of said magazine along the empty portion of said track circuit to the other extremity of said magazine. 15
15. In a display device having a window therefor and comprising an elongated track circuit 20 traversing said window, display holders movably restrained in said circuit, a magazine for said holders composed of that portion of said track circuit including the side traversing said window and extending beyond said window to include the 25 extremities of said elongated track circuit, and motor driven means to convey one holder at a time from one extremity of said magazine along the empty portion of said track circuit to the other extremity of said magazine. 30
16. In a display device having a window therefor and comprising a compacted group of display holders movably restrained in an elongated circuit therein, motor operated conveyor means located within and normal to said circuit, means 35 on said conveyor and co-operating means on the back of said holders to permit said conveyor to engage said holders, one at a time, at one end of said elongated circuit and to disengage said holder at the other end of said circuit. 40
17. In a display device having a window therefor and comprising an elongated track circuit traversing said window, display holders movably restrained in said track circuit, a motor driven conveyor circuit within said track circuit, and a 45 magazine for said holders composed of that portion of said track circuit embracing both ends thereof and including the side traversing said window filled with compacted display holders. 50

CHAS. ROBERTS.
